CLAIM

The ornamental design for a hygrothermograph, as shown and described.

DESCRIPTION

FIG. 1 is a first perspective view of a hygrothermograph showing the new design;

FIG. 2 is a second perspective view of the hygrothermograph showing the new design;

FIG. 3 is a front view thereof;

FIG. 4 is a rear view thereof;

FIG. 5 is a left view thereof;

FIG. 6 is a right view thereof;

FIG. 7 is a top view thereof;

FIG. 8 is a bottom view thereof;

FIG. 9 is a right front side perspective view of the hygrothermograph in use; and,

FIG. 10 is a left rear perspective view of the hygrothermograph in use.

(Continued)

The broken lines in the drawings show portions of the hygrothermograph which form no part of the claimed design.
